UNITED STATES PATENT OFFICE

NILS A. WAHLBERG, OF WILKINSBURG, PENNSYLVANIA, ASSIGNOR TO WESTINGHOUSE ELECTRIC & MANUFACTURING COMPANY, A CORPORATION OF PENNSYLVANIA

INSULATOR CONNECTER

Application filed February 19, 1921. Serial No. 446,401.

My invention relates to connectors and particularly to connectors for strain insulators.

The object of my invention is to provide a strain-insulator connector that shall be simple in construction and manipulation, economical to manufacture and reliable and effective in operation and that shall be symmetrical and pleasing in appearance.

Heretofore, certain connectors for strain 10 insulators of the porcelain-block or petticoat types, having right-angularly related seats or openings and interlinked metal members disposed in the openings, have been comparatively complicated and expensive in construction, of large size and unsymmetrical in form 15 and have had other undesirable characteristics, as in those embodying stranded metal cables. The latter usually require splicing or other construction of complicated and expensive character.

In practicing my invention, I provide a connector, for disposition at one end of an insulator, comprising a member constructed of a section of standard rod or wire and 25 formed to substantially C-shape by a simple bending operation. The free ends of the member are bent inwardly for insertion through openings in a second member and are threaded to receive holding nuts. The 30 second member is constructed of standard strap or sheet metal bent to substantially loop shape, with the above mentioned openings at an intermediate portion thereof. Apertured 35 projections at the free ends of the second looped member are adapted to attach the insulator to a supporting device or to an adjacent similar insulator.

The single figure of the accompanying 40 drawing is a side elevational view of a strain insulator on which connectors embodying my invention are mounted.

A block 1 of insulating material, preferably of porcelain, is provided with right-45 angularly related openings 2 and 3, of laterally-curved contour, for the reception of interlinked metal members 4 and 5, respectively. The latter, preferably constructed of 50 standard rod or wire material, are shaped and mounted in position in the block 1 by

bending and have inwardly-bent, threaded outer ends 6 and 7.

End or terminal members 8 and 9, preferably constructed of standard flat strap or sheet metal, are bent to substantially pentagonal shape having spaced apertured projections 10 extending outwardly from the ends of adjacent or intersecting sides 11 and 12 of the pentagonal portion thereof.

Sides 13 and 14 of the members 8 and 9 are 60 provided with openings 15 for the reception of the ends 6 and 7 of the members 4 and 5. Nuts 16 are provided on the ends 6 and 7 to hold the members 4 and 8 and the members 5 and 9 together.

In assembling the device, the ends 6 and 7 are first bent to shape and the members 4 and 5 placed in the openings 2 and 3 while the ends 6 and 7 are spaced apart a distance sufficient to permit their ready placing in the 70 openings. With the members 8 and 9 in the positions shown, the ends 6 and 7 are then bent to final position and the nuts 16 mounted during this bending operation.

By having the ends 6 and 7 inwardly bent 75 towards each other, the terminal members 8 and 9 are rendered smaller and more compact and are more readily constructed of standard sheet or strap material. The device is thereby, rendered more economical and of 80 less weight than it would be if the ends 6 and 7 were merely straight continuations of the legs of the members 4 and 5, respectively.

The structure constitutes a simple and effective, unitary, readily-transportable device 85 that is economical to manufacture. Further, it is of symmetrical form and pleasing appearance, has relatively short overall length and may be quickly installed by the simple expedient of placing bolts through 90 the openings 15.

While I have shown and described a particular form of my invention, changes may be effected therein without departing from the spirit and scope thereof, as set forth in the 95 appended claims.

I claim as my invention:

1. A tension connector comprising an element of substantially U-shape having its free ends inclined toward each other, a member 100

having an intermediate portion of substantially **C**-shape and end portions projecting outwardly therefrom, said intermediate portion having a pair of openings through which it receives said inclined ends, and enlargements on said inclined ends inside said intermediate portion.

2. A tension connector comprising an element of substantially **U**-shape having the free ends of its side arms inclined toward each other, a member having an intermediate portion of substantially **C**-shape disposed with its closed rear side adjacent to said free ends and having its arms extending away from the member of **U**-shape in the general direction of said first arms and means for holding said inclined ends in operative relation to said closed rear side.

In testimony whereof, I have hereunto subscribed my name this 11th day of February, 1921.

NILS A. WAHLBERG.
